RAILWAY PASSENGER CAR

George W. Calhoun, Merwood Park, and Norman W. Fesmire, Willow Grove, Pa., assignors to The Budd Company, Philadelphia, Pa., a corporation of Pennsylvania

Application May 27, 1955, Serial No. 36,252

Term of patent 14 years

(Cl. D66—1)

Fig. 1 is a side elevation of a railway passenger car showing the design, the other side being a reverse duplicate;

Fig. 2 is a top plan on a reduced scale;

Fig. 3 is a transverse section of one side of the car, the view being taken on the line 3—3 of Fig. 1; and

Fig. 4 is an end elevation, the other end being the same.

The essential features of our design reside in the portions shown in full lines. The car ends are conventional.

We claim:

The ornamental design for a railway passenger car, substantially as shown and described.
